UNITED STATES PATENT OFFICE.

JOSEPH LUCCINO, OF BROOKLYN, NEW YORK.

FOLDING COT.

1,408,015.

Specification of Letters Patent. Patented Feb. 28, 1922.

Application filed January 17, 1921. Serial No. 437,748.

To all whom it may concern:

Be it known that I, JOSEPH LUCCINO, a citizen of the United States, residing at Brooklyn, in the county of Kings and State of New York, have invented certain new and useful Improvements in Folding Cots, of which the following is a specification.

This invention relates to folding cot-beds and particularly to a cot-bed of this type which may be readily and easily folded into a compact structure so as to occupy a minimum of space and to facilitate the portage and transportation of the same, and which at the same time will be simple in construction, economical to manufacture, durable in use, easily manipulated, and comfortable to sleep upon.

A further object of this invention is to provide a folding cot-bed having a minimum of connecting links and operating parts, and having a main or relatively stationary mattress section provided at each end thereof with a pair of foldable mattress sections pivoted or hinged together and to the main mattress section, the construction being such that the bed can be collapsed or folded to occupy very small space, merely by swinging the end sections inwardly to a position above and parallel to the main section, the main section having a length at least as great as the combined length of the two end or outer sections, the latter in folded position being located in non-overlapping relation thereby providing an increased length-wise housing space and at the same time a compact structure.

Other objects of the invention will appear during the course of the ensuing description, reference being had to the accompanying drawing forming a part of the specification wherein like reference characters indicate similar parts throughout the several views and wherein Fig. 1 is a perspective view of my improved cot-bed in an open or unfolded position; Fig. 2 is a side view thereof in its folded position; Figs. 3 and 4 are detail views indicating successive steps in the operation of the parts and Fig. 5 is a detail view indicating the manner of operation of the outer sections.

In the preferred form herein shown and described my improved folding cot comprises a main or relatively stationary mattress section 10, and a pair of inter-connected swinging sections 11 and 12 pivoted or hinged thereto at each end. Each con-

necting mattress section 11 is pivoted or hinged intermediate its length as at 13 to the main mattress section 10. One end 14 of each section 11 is pivoted or hinged to an outer or end section 12 and at its opposite end has connected thereto a pair of folding legs 15. In the present instance in order to provide space for the legs 15 between the sections 10 and 11, the latter preferably comprises a pair of members or side bars 30 and 31 suitably secured together. The member 31 has an offset portion 32 and is pivotally connected to the leg 15 as at 17. The folding legs 15 are preferably pivoted as at 15' to depending brackets 16 rigidly secured to the side rails of the main mattress section 10. Suitable lost motion slots 18 are provided in each leg 15 for the movement of the pivot 17 thereby ensuring the necessary flexibility during the operation of the various parts.

In order to provide suitable supporting means for the outer or end folding sections 12 each section thereof is provided with a pair of foldable legs 19 pivoted as at 19' to the side rails of section 12 and adapted, upon swinging said sections to their folded position above the main section 10, to be moved to a position substantially parallel with the section 10. This operation as will be observed is controlled by means of a link 20 pivoted to the upper end 20' of each movable leg 19 and also pivoted to each intermediate section 11. In order to strengthen the structure and maintain the legs 19 in parallel relation, I provide suitable tie bars or braces 25 connecting the adjacent legs 19 at each end of the bed.

It will be seen that I have provided a very simple but efficient cot-bed which may be readily manipulated and converted from an open or unfolded position into a compact structure occupying a minimum of space as illustrated in Fig. 2. In operation in order to fold or collapse my improved bed or cot from the position illustrated in Fig. 1 it is merely necessary to grasp the outer section 12 and swing the same upwardly and inwardly to a position above and substantially parallel to the main section 10. During this operation due to the fact that each intermediate section 11 is pivoted to the main section 10, this section upon being swung about the axis 13 will act as a lever to swing the legs 15 in an opposite direction and to a position substantially parallel with the side

rails of the section 10 and below the same. Thus it will be readily observed that the effect of swinging the section 12 to an inverted position above the bed is to swing 5 the section 11 about its axis 13 to a position substantially at right angles to the position of the main section 10 thus providing between the outer sections 12 and the inner section 10 suitable space for the stuffed mat- 10 tress or bed-clothes 26. The outer sections 12 in folded position are located in horizontal and endwise alinement with each other thereby providing sufficient housing space for the mattress without causing the ends of 15 the latter to be overlapped one above the other.

Furthermore due to the fact that each leg 15 is pivoted adjacent to one end thereof as at 15' to the bracket 16, and due to the fact 20 that the side rails of the section 11 are pivoted as at 17 to the legs 15, the sections 11 therefore when swung from a horizontal position to a vertical position as illustrated in Figs. 5, 4 and 3, due to the inter-connections 25 will swing the legs 15 from a vertical position to a horizontal position, the one having a swinging movement in a direction opposite to the swinging movement of the other. The legs 15 have each a fulcrum intermediate its length at 15' upon the main section 10, and are operated by the intermediate section 11 by virtue of the direct connection at one end 17 with the free ends 30 of the intermediate bed section. Also it will be observed that the supporting legs 19 and 15 are automatically controlled and operated through the medium of the sections 11 and upon folding the bed from the position of Fig. 1 to the position of Fig. 2 the supporting 35 legs 19 and 15 will be swung from a vertical position to a horizontal position toward each other. Each of the supporting legs 15 are provided with suitable casters 27 whereby in its folded position the bed is 40 adapted to rest thereupon and may be easily shifted or moved from place to place. In the present instance the several sections of the framework are all connected by a single stuffed mattress support herein shown as a 45 spring or spring mattress 40 which may be connected at its ends to the framework by suitable coiled springs 41.

When it is desired to unfold my improved cot-bed from the position illustrated in Fig. 2, it is merely necessary to grasp each outer section 12 and swing the same through the successive positions illustrated in the Figs. 3 and 4 to the position shown in Fig. 5 wherein the section 12 is in an upright position 50 at right angles to the section 11 which has assumed a horizontal position in the operation. From an inspection of Fig. 5 it will be observed that the foldable legs 19 are not opened or moved during this operation 55 so that the operation is not hampered by the

swinging thereof, but that the legs 15 alone are swung to their supporting position and thus support the weight of the bed, making it much easier to manipulate the other parts, whereas if it were attempted to first open 70 the sections 12 and consequently both pair of legs at the same time the operator would have to support the entire weight of the bed off the floor, which would be a very difficult thing to do. Hence owing to the particular 75 location of the several pivots between the legs 19, links 20, and bed section 12 the legs 19 are locked in position at this time and it is practically impossible to open or unfold 80 the same by an attempt to do this by moving the bed section 12 until the legs have been grasped and swung outwardly (as illustrated in dotted lines in Fig. 5) thereby swinging the pivots 19' and bed section 12 85 outwardly and downwardly which thus permits the section 12 to be readily swung to a horizontal position and the legs 19 swung to their supporting position.

In other words it will be seen with reference to Fig. 2 and Fig. 5 in full lines, that 90 normally the legs 19 in closed position are substantially in alinement with the section 12, and hence the several pivots 20', 19', and 14, are in such approximate alinement as to form substantially a dead center. Thus 95 when attempting to swing the sections 12 downwardly from the full line position of Fig. 5, the links 20, by virtue of this relation of pivots, act as a locking means and hence, at this time, the section 12 together with the 100 legs 19 are immovable. Therefore in order to accomplish the unfolding of the legs 19 and sections 12, it is necessary to shift the pivots 19' with relation to the pivots 20' and 14 in order to permit the links 20 to be actuated and to unfold the legs 19. This is accomplished merely by swinging the legs 19 outwardly a small distance as shown in dotted lines in Fig. 5, and thereupon by 105 grasping the ends of section 12, the same together with the legs 19 can be readily 110 swung to the position in Fig. 1.

My cot-bed is opened in the manner above described whereby the legs 15 are first 115 swung to a position to support the entire bed, and thereupon the legs 19 are unfolded to support the sections 12 so that the user does not have to contend during the opening of the bed with two sets of swinging legs while supporting the entire weight of 120 the mattress. During the operation of the legs 15 by the intermediate sections 11 each pivot 17 slides freely in its slot 18, the latter being important for flexible operation 125 of the parts. It will be further observed that the distance between the pivots 13 and 17 of the section 11 is substantially the same as the distance between the pivot 15' and the outer end of the slot 18, or between 130 the pivot 15' and the normal posi-

tion of the pivot 17 in the slot 18. Hence the essential purpose of the bracket 16 is to space the pivot 15' from the central longitudinal axis of the section 10 by a distance 5 substantially equal to the distance between the pivot 15' and the normal position of pivot 17 in the slot 18.

Although I have described a preferred embodiment of my invention it is to be understood that I do not limit myself to the construction herein shown and described but may make such changes as will come within the scope of the appended claims:

1. A bed structure comprising a main bed section, an intermediate bed section, and an outer bed section connected together, and automatically foldable legs for the bed adapted to be operated upon a predetermined movement of certain of said sections, 15 and means for automatically restricting the movement of certain of said legs, whereby the others may be operated prior thereto.

2. A cot bed comprising a relatively stationary main bed section having at one end 25 an intermediate bed section and an end bed section pivotally connected together and to the main section, said end section being foldable relatively to the main bed section and forming therewith a housing space for 30 a mattress, and a plurality of supporting legs automatically foldable during a predetermined movement of the bed sections and connected to both said main section and also said intermediate section.

3. A foldable bed structure comprising a 35 plurality of bed sections pivotally connected together and including an inner, and an intermediate section, said inner section being pivotally connected to the intermediate 40 section intermediate its length.

4. A foldable bed structure comprising a plurality of bed sections pivotally connected together and including an inner and an intermediate section, said inner section being 45 pivotally connected to the intermediate section intermediate its length, and automatically foldable legs for the inner section controlled by the free ends of said intermediate section.

5. A foldable cot-bed comprising a main section, a pair of end sections, and a pair of intermediate sections, one thereof connecting each end section with the main section and foldable to form a housing space 55 for the mattress, and supporting legs for the several sections automatically foldable with the sections, certain of said supporting legs being pivotally connected with the main section and certain thereof with the end sections, and certain thereof having connection 60 with the intermediate sections whereby the latter are operative to control the movement of said supporting legs.

6. A foldable cot-bed comprising a main section, a pair of end sections, and a pair

of intermediate sections, one thereof connecting each end section with the main section and foldable to form a housing space for the mattress, and supporting legs for the several sections automatically foldable 70 with the sections, certain of said supporting legs being pivotally connected to the main section, and certain thereof to the end sections, said supporting legs being controlled by said intermediate sections. 75

7. A foldable cot bed comprising a main bed section, an outer bed section and an intermediate bed section, said outer and intermediate sections being foldable relatively to the main bed section, and supporting 80 legs for the bed automatically and reversely foldable with the folding sections.

8. A foldable cot-bed comprising a main section a pair of end sections, and a pair of intermediate sections, one thereof connecting each end section with the main section and foldable to form a housing space for the mattress, and a plurality of foldable legs for the several sections automatically foldable with the sections, a pair thereof 85 being pivoted to the main section and a pair thereof to an end section, and means for connecting said legs to the intermediate section whereby upon folding the bed said last section will be operative to swing certain of 90 said legs to a position above the bed, and certain thereof in an opposite direction to a position below the bed.

9. A foldable cot-bed comprising a main section, a pair of end sections, and a pair 100 of intermediate sections, one thereof connecting each end section with the main section and foldable to form a housing space for a stuffed mattress, supporting means for the several sections automatically foldable 105 with the sections and connected to the intermediate section for movement therewith, whereby upon folding said bed said intermediate section will be effective to swing certain of said supporting means in one direction to a position above the bed and certain of said supporting means in an opposite direction to a position below the bed. 110

10. A foldable cot-bed comprising a main section, an end section, and an intermediate 115 section hingedly connected at one end to said end section and connected intermediate its length to the main section, a pair of foldable legs pivoted to the main section and to the opposite end of said intermediate section, 120 a second pair of foldable legs pivoted to the end section and connected to the intermediate section, whereby upon swinging the end section above the main section to a folded position said intermediate section will be 125 effective to swing said first legs in one direction to a position below the bed and said last legs in an opposite direction to a position above the bed.

11. A cot bed comprising a main bed sec- 130

- tion, and end bed section and an intermediate bed section connected together, said end and intermediate sections being foldable relatively to the main section to form a housing space for a mattress, and means for restricting the movement of the end section relatively to the intermediate section during a predetermined unfolding movement of the latter.
10. 12. A bed structure comprising a plurality of bed sections pivotally connected together, and a pair of automatically foldable legs therefor, said legs having each a fulcrum intermediate its length upon one of said bed sections, and a direct operating connection at one end with another of said bed sections.
15. 13. A cot bed comprising a main bed section, an end bed section and an intermediate bed section connected together, said end and intermediate sections being foldable relatively to the main section to form a housing space for a mattress, means for restricting the movement of the end sections relatively to the intermediate section during a predetermined unfolding movement of the latter, said sections forming a full length bed in the direction of unfolding, and reversely folding supporting legs for the cot automatically foldable with the folding sections.
20. 14. A folding cot bed comprising a middle section and a pair of sections at each end thereof, a pair of said sections being pivoted each intermediate its length to the middle section, supporting legs connected to one end of each of said last sections, and means for pivotally supporting said supporting legs in spaced relation with said middle section.
25. 15. A folding cot comprising a middle section, a pair of intermediate sections, and a pair of end sections, said intermediate sections being pivoted each intermediate its length to said middle section, legs slidably connected to one end of each intermediate section and spacing means for pivotally supporting said legs in spaced relation with said
30. 16. A foldable cot comprising a main section, a pair of end sections, and a pair of intermediate sections and supporting means for the sections automatically foldable with the sections, said cot being unfolded by swinging the end sections to unfold certain of said supporting means prior to the others, said last supporting means being locked from movement during such operation.
35. 17. A folding cot comprising a middle bed section, and a pair of bed sections at each end thereof foldable toward each other, leg spacing brackets secured adjacent to each corner of the middle section, a slotted leg pivotally secured to each bracket, and a pivot for each leg carried by one of said sections and cooperating with the slot.
40. 18. A folding bed structure comprising a main bed section, a plurality of bed sections connected thereto and automatically foldable legs for the bed, one of said legs and one of said sections having one a slot and the other a part cooperating with said slot whereby said leg will be operated from said last section.
45. 19. A folding cot comprising a middle section and a pair of bed sections at each end thereof foldable toward each other, legs slidably connected to certain of said sections, and leg supporting means carried by another of said sections and pivotally connected to the legs for maintaining the same in spaced relation relatively to said last section.

Signed at 1822 Park Row Building, New York city, New York, this 10th day of January, 1921.

JOSEPH LUPPINO.
